CONTAINER WITH INFOLDED BOTTOM
CLOSURE

Harry B. Egleston, Livonia, and Charles Z. Monroe, Detroit, Mich., assignors to Ex-Cell-O Corporation, Detroit, Mich., a corporation of Michigan
Filed Sept. 7, 1961, Ser. No. 136,505
10 Claims. (Cl. 229—43)

The present invention relates to packaging and more specifically to a container bottom closure construction. The invention finds particular, but by no means exclusive, utility in disposable containers adapted for distribution of milk and other dairy products.

This application is a continuation-in-part of our copending U.S. application Serial No. 707,259, filed January 6, 1958, now abandoned.

One form of container of the type just noted and presently in wide commercial use is disclosed in U.S. Patent No. 2,750,095, issued June 12, 1956, on the application of Carroll R. Alden (Reissue No. 25,021, issued August 8, 1961). Such a container is customarily erected from a flat blank formed of sheet stock such as paperboard which has been cut to shape and impressed with an appropriate pattern of score lines. These lines define a plurality of side panels together with corresponding upper and lower extension flaps or closure members.

The usual procedure in erecting the container is to form the blank into a polygonal tube open at both ends and then to close the lower or bottom panel extensions, retaining them in place by means of a suitable adhesive. It is presently the practice to coat or impregnate the exposed surfaces of the erected tube by immersing it in a bath of molten paraffin. Following this operation, the container is cooled to harden the paraffin and is then filled with a selected product such as milk. The container top is closed and sealed by pressing the closure elements together with heated jaws, thereby fusing the paraffin coating so that all cracks are sealed. In order to supplement the strength of the paraffin bond, the top closure elements may be stapled together.

Although paraffin coated containers of the above-described type have been commercially successful, there are certain disadvantages inherent in their use, one of the most marked of which involves the paraffin coating. In the first place, a suitable dip tank of molten paraffin must be maintained as part of the packaging machinery at the dairy or processing plant. This, along with the extra care and attention required on the part of the operator, plays a part in increasing the cost of the container and finally of the ultimate product. Also, under certain extreme conditions, globules of the paraffin coating may flake off of the container walls. While this does not impair the sanitary integrity of the contents, it does tend to impair consumer acceptance of the container.

It has now been discovered that paperboard of the quality heretofore used for dairy product containers can be economically coated with heat and pressure sensitive thermoplastic substances. The thermoplastic substance used is desirably one which is inert to the substances to be packaged, is strong and durable, is inexpensive, and is easy to apply in sheet form onto the paperboard. A coating of this sort renders the paper sheet material resistant to fluids which would be packaged in the container including such acidic products as milk. One example of such a thermoplastic substance which is useful for packaging dairy products is polyethylene. It will be apparent to those skilled in the art, however, that other thermoplastic materials, such as polyvinyl chloride, polyvinylidene chloride, polyvinyl chloride and acetate copolymer, and polypropylene, to name only a few, will find use under favorable circumstances.

2

Paper sheet stock for forming containers is initially supplied in the form of rolls, and as the stock is produced it can be coated on both sides with a layer of polyethylene thermoplastic material. One method of accomplishing this is by heating and stretching the polyethylene and applying it when hot directly onto the surface of the paper to which it becomes tightly bonded. The surface of the paper to be used for the outside of the blank is generally coated with a layer approximately $\frac{3}{4}$ of a mil thick while the inside surface of the sheet is coated with a layer of polyethylene approximately 1 to $1\frac{1}{2}$ mils thick.

The general aim of the present invention is to provide a new and improved container formed of thermoplastic sheet material, or thermoplastic-coated paperboard sheet material, and which will be strong, simple to erect, close and seal, and susceptible of high volume economical production for packaging milk and other comestibles.

A more specific object of the present invention is to provide a container of the above type having surfaces of sanitary heat and pressure sensitive thermoplastic material which not only protects the contents of the container against admission of harmful substances but also serves as a sealing adhesive for effecting tight closure and sealing of the container.

Another object of the invention is to provide an improved container of the character set forth and having a bottom closure susceptible of automatic closing and sealing to form a strong leak-proof bottom on the container which will remain fluid-tight even under severe conditions of use, such as being dropped on a bottom corner.

Still another object of the invention is to provide a container of the foregoing type and having a bottom closure with at least three plies of integrally connected stock at each bottom corner area and a minimal length of raw edge exposed to the interior of the container and the contents thereof.

Other objects and advantages of the present invention will become apparent as the following description proceeds, taken in connection with the accompanying drawings, wherein:

FIGURE 1 is a perspective view of an illustrative closed and sealed container embodying the present invention.

FIG. 2 is a layout view of a blank from which the container in FIGURE 1 was erected and showing the inside surface thereof.

FIGS. 3, 4, 5 and 6 are fragmentary perspective views illustrating sequentially various steps in forming the bottom closure of the container of FIGURE 1.

FIGS. 7, 8, 9 and 10 are fragmentary perspective views similar to FIGS. 3 to 6 but showing another form of container bottom closure also embodying the invention.

FIG. 11 is a layout view of the inside face of a blank similar to that shown in FIG. 2 but adapted to define the bottom closure of FIGS. 7 to 10.

FIG. 12 is an outside bottom view of the container of FIGURE 1 and showing certain embossing of the latter in accordance with a further aspect of the invention.

FIG. 13 is an outside bottom view similar to FIG. 12 but showing a container having the bottom closure of FIGS. 7 to 10.

FIG. 14 is a view of the inside face of the container bottom of FIG. 13, looking in the direction indicated by the line 14—14 in FIG. 10.

While the invention is susceptible of various modifications and alternative constructions, certain illustrative containers have been shown in the drawings and will be described below in detail. It should be understood, however, that there is no intention to limit the invention to the specific forms disclosed. On the contrary, the intention is to cover all modifications, alternative constructions, equivalents and uses falling within the spirit and scope of the invention as expressed in the appended claims.

Referring more specifically to the drawings, there is shown a container 20 (FIG. 1) which represents an illustrative embodiment of the present invention. The container 20 is formed from paper or other suitable sheet material and is self-sustaining in shape. To render the sheet material fluid-tight and capable of holding such acidic liquids as milk, the sheet material has surfaces of, or is coated with, a thermoplastic material of the type exemplified by polyethylene.

The container 20 comprises a tubular body 21 which in the present instance happens to be substantially square in cross section. At its base the body 21 is provided with a bottom closure 22. The upper end of the body 21 in this instance terminates in what will be recognized as the familiar gable top type of end closure 23 which is surrounded by a central laminar rib or truss 24. The top end closure has incorporated therein an extensible spout for dispensing the contents of the container.

The container 20 is fashioned from a flat blank 25 of high-grade paperboard coated with a layer of polyethylene thermoplastic material. By means of an appropriate pattern of score lines the blank 25 (the inner face of which is illustrated in FIG. 2) is divided into a plurality of panels and areas which are utilized for the walls of the container and the closure parts when the container is erected. The central and major area of the blank becomes the body 21 of the container and is defined by spaced apart transverse score lines 26, 28, running in substantially parallel relation across the face of the blank. Intersecting the lines 26, 28, at spaced intervals therealong are a series of perpendicular score lines 29, 30, 31, and 32, which define, in the central and major area of the blank, side panels 34, 35, 36, and 37 together with a fractional side panel or side seam flap 38. When the container is erected, the latter is adhesively secured in overlying relation with the inside face of the side panel 34.

It should be noted that the transverse score lines 26, 28 are not continuous but are formed in staggered portions interrupted by the perpendicular score lines 29, 30, 31, and 32. The purpose of this staggered scoring is to accommodate the thickness of the paper as it is bent along the score lines when the container is erected and thus prevent crowding of the paper at the various corner junctions of the score lines. This not only enhances the strength and appearance of the finished container but facilitates its erection and closure by automatic machinery.

Connected to the lower edges of the side panels along the lower transverse score line 28 are bottom closure panels 39, 40, 41, and 42. Accordingly, alternate side panels 34, 36 have respectively connected therewith opposed bottom closure panels 39, 41. The latter in turn include respectively a tuck-in flap 50 and an overlying or outside overlap flap 51. The tuck-in flap 50 is relieved or recessed at 52 so that it receives the adjacent end 53 of the side seam flap when the bottom closure is sealed. In this manner an extra thickness of sheet material at one edge of the bottom closure is avoided.

Similarly, alternate side panels 35, 37 have connected therewith along the transverse score line 28, opposed triangular infold panels 40, 42, respectively. The infold panel 40 is flanked by triangular fold-back panels 55, 56 connected thereto along converging score lines 58, 59, starting at the intersections between the perpendicular score lines 29, 30 and the transverse score line 28, converging downwardly and intersecting at the cut lower edge of the blank (as viewed in FIG. 2). By the same token, infold panel 42 is flanked by fold-back panels 60, 61 connected thereto along fold lines 62, 63. In addition to the above connections, triangular fold-back panel 56 is connected to bottom panel 39, panel 55 is connected to bottom panel 41, panel 61 is connected to panel 41, while panel 60 is connected to the bottom portion 53 of the side seam flap 38.

Integral with the upper ends of the side panels, but separated therefrom by the transverse score line 26, are a plurality of panel extensions which give the top of the

container 20 its characteristic gable shape. These areas include a transverse score line 66 generally parallel to the score line 26 and spaced between the latter and the top edge of the blank 25. The areas below the line 66 define roof panels 68, 69 and triangular end and fold-back panels 75, 78, 79 and 76, 88, 89 of the top closure. The areas above the line 66 define the parts of the central laminar rib 24, namely, inner rib panels 84, 85, 94, 95, outer rib panels 70, 71, and sealing flaps 72, 73. Again score line 66 is not a straight line but includes staggered portions 66a, 66b, 66c and 66d corresponding respectively to the panels 34, 35, 36 and 37, for accommodating the thickness of the paper when the container closure is folded.

The blank 25 is transformed into a completed container as illustrated in FIG. 1, by first folding it upon itself to form a flat tube and adhesively securing the side seam flap 38 and its extensions 53, 98, 99 to the inside faces of panels 39, 34, 78 and 84. While it is possible to utilize the polyethylene coating as an adhesive for the side seam, it may in some instances be feasible to apply an additional amount of adhesive thereto for purposes of forming the side seam. Such added adhesive is desirably resistant to heat at the melting point of the polyethylene or other coating on the container so that the side seam remains tight during subsequent closing and sealing operations. One polyethylene base adhesive used for the side seam has a melting point of about 500° F.

The flattened blank tube is then erected into a tube of substantially square cross section (FIG. 3) and the bottom closure is completed. Accordingly, the score lines or creases 58, 59, 62, and 63 are broken or given a prebend by folding the triangular infold flaps 40, 42 inwardly towards each other (FIG. 4). The tuck-in flap 50 is then in position for insertion beneath end panel 39 and above the triangular fold-back flaps 56 and 60 so that the bottom panel 39, which includes the sealing flap 51, overlies end panel 41, which includes the tuck-in flap 50 (as viewed in FIG. 5).

In order to seal the bottom of the container the bottom closure panels are first broken but before they are finally folded they are subjected to a source of intense heat so as to melt or at least activate and render adhesive-ly active the coating of polyethylene on both surfaces of the bottom closure panels. When a polyethylene coating is used the heat must be sufficient to partially melt the coating which melts between about 230 and 275° F., depending upon its density. These panels are then folded together and the tuck-in flap 50 is inserted in place. When the bottom closure is completed it is subjected to pressure between cooled pressure pads to cool and solidify the polyethylene plastic adhesive and thus produce a completely sealed bottom end closure.

Provision is made for obtaining an exceptionally tight seal of the bottom closure 22 when finally completed. This is accomplished in large measure by constructing the bottom closure parts so that the cut edges of the triangular fold-back panels 55, 56, 60 and 61, which abut each other in the completed bottom closure, will enter into positive abutting engagement with each other prior to completion of the bottom closure. In furtherance of such objective, the bottom closure panels 40 and 42 are so proportioned that the combined length of the triangular fold-back panels 55, 56, as well as the combined length of the triangular fold-back panels 60, 61, normal to the score line 28, will be slightly greater than the base width of each triangular bottom closure panel measured along the score line 28 (FIG. 2). Stated another way, and in the present instance, the bottom closure panels are proportioned so that those portions of the vertical score lines 29, 30, 31 and 32, joining the bottom closure panels 39, 40, 41 and 42, and defining a side of each of the triangular fold-back panels, are slightly longer than one-half the width of each triangular bottom closure panel measured along the score line 28. Thus, as the bottom closure panels are folded into engagement and approach

the position illustrated in FIG. 5, the cut edges of the triangular fold-back panels 55, 56, 60 and 61 will enter into positive abutting engagement with each other. With further downfolding of the bottom closure panels from the position of FIG. 5 to the fully downfolded position shown in FIG. 6, and the application of sealing pressure thereto in the latter position, the paperboard is crowded together under substantial compression in its own plane as well as transversely thereof. The tightness of the ultimate bottom seal is thus materially increased.

When the container has been erected and the bottom closure sealed, it is normally in a sanitary condition. In some instances, however, it may be subjected to further sterilization as by irradiation with ultraviolet light or by dipping in a tank of water at approximately 200° F. The sterilized containers are then filled with the desired product.

To seal the container top closure, the parts thereof are infolded into gable form. During the course of such action the triangular panel crease lines 89, 81, 90, 91 are broken by infolding the triangular end panels 75, 76 toward each other. The inner and outer rib panels and sealing flaps 72, 73 are then heated on both sides, as was done with the bottom flaps, to adhesively activate the polyethylene thermoplastic coating. The container is then closed as by passing its top portion between a pair of converging shoes which bring the adhesively activated rib panels and sealing flaps together to complete the gable top structure. The rib panels and sealing flaps are therewith subjected to substantial sealing pressure which may be derived from cooled pressure jaws leaving the top closure in sealed condition as illustrated in FIG. 1. The top closure seal may, of course, be broken by the user through deliberate application of external forces to effect partial disassembly of the top rib 24 and expose the pouring spout housed therein.

For the purpose of further enhancing the fluid-tight integrity and the durability of the seal in both the bottom and top closures of the container 20, an additional precaution may be taken, particularly where the container is used for packaging fluids. This involves the application of increased pressure to selected areas of the closure parts during the pressure sealing operation, producing indentations or embossments in the closure plies which effectively close up incipient fluid escape channels. In the present instance, these areas of increased pressure or embossing on the bottom closure are represented by the crosshatched areas in FIG. 12.

Referring more specifically to FIG. 12, the outside bottom view of the container 20 is there shown. Rectangular embossed area 105 on overlying or outside bottom panel 39 has been pressed inwardly for almost the thickness of one ply of stock. This effectively blocks the incipient leakage channels which would otherwise occur along the free-cut edge of the bottom tuck-in flap 50 and the side seam flap 53. Embossments 106, which in this instance happen to be circular, are located primarily on the overlying or outside bottom panel 39 and are adapted to block off channels at the abutting edges of bottom fold-back panels 55, 56, 60, 61. In addition, the embossments 106 enhance the sealing between the bottom fold-back panels and the flaps 50, 51, 53, on the one hand, and between the bottom fold-back panels and the bottom infold panels 40, 42, on the other hand. Similarly, embossments 108, which happen to be wedge-shaped, are situated adjacent the lateral edges of the overlying bottom flap 51 and close the incipient channels between the underlying abutting plies of the bottom tuck-in flap 50, side seam flap 53, and the panels 40, 55, 56, and 42, 60, 61.

The container 20 may have another form of bottom closure 22a differing in some respects from the bottom closure 22 described above but also embodying the present invention. Turning now to FIGS. 7 to 11, inclusive, 13 and 14, wherein like reference numerals designate

like parts described earlier herein, it will be noted that the bottom closure 22a bears considerable similarity to the bottom closure 22.

In this instance, the container 20 is formed from a flat blank 110, the inside face of which is shown in FIG. 11, having many parts in common with the blank 25 shown in FIG. 2 and already described herein. The blank 110 thus includes transverse score lines 26, 28, 66, perpendicular score lines 29, 30, 31 and 32, side panels 34, 35, 36, 37, and side seam flap 38. Above the score line 26, the blank includes a series of top closure elements which in this instance happen to be similar to those of the blank 25. Below the score line 28, the blank 110 includes triangular bottom closure panel 40 flanked by triangular fold-back panels 55, 56, all constituting an extension of the side panel 35, and triangular bottom closure panel 42 and fold-back panels 60, 61, all being an extension of side panel 37. Alternating with the panels 40 and 42, are major bottom closure panel 111, constituting an extension of the side panel 34, and bottom closure panel 112, constituting an extension of the side panel 36. In addition, there is panel extension 114 of the side seam flap 38.

In the bottom closure 22a, the major bottom panels 111, 112 fold relative to one another in a relationship which is just the opposite from that of their counterparts 39 and 41 in the closure 22. Thus, the free-cut marginal edge portion of panel 111 has defined thereon a tuck-in flap 115, while the free-cut marginal edge portion of the panel 112 has defined thereon an overlying or outside overlap flap 116. The ends of the tuck-in flap 115 are chamfered or tapered as at 118 to facilitate entry of the flap 115 between the triangular fold-back panels 55, 61 and the inside face of the overlying flap 116 of bottom panel 112. In addition, the end of the side seam panel extension 114 is relieved or chamfered as at 119, while the end portion of the overlying flap 116 which faces it is also relieved or chamfered at 120.

Completion of the formation of the bottom closure 22a is similar to that of the closure 22 and is illustrated sequentially in FIGS. 7, 8, 9 and 10. Starting with the blank 110 in open-ended tubular form, illustrated in FIG. 7, the triangular bottom panels 40, 42 and their associated fold-back panels 55, 56, 60, 61, as well as major bottom panels 111, 112 are first broken inwardly and downwardly, as illustrated in FIG. 8. They are then subjected to fairly intense heat, as mentioned earlier herein, so as to render adhesively active the plastic material, such as polyethylene, on both surfaces of the bottom closure panels. The infolding or downfolding is then continued rapidly, the tuck-in flap 115 being first slid beneath the inside face of the overlying flap 116 and therewith inserted between the inside face of the overlying bottom panel 112 and adjacent triangular fold-back panels 55, 61. Prior to the completion of the downfolding, with the bottom closure in the condition illustrated in FIG. 9, the flap 116 substantially overlies the tuck-in flap 115. Due to the fact that the triangular fold-back panels 55, 56, 60, 61 are constructed with the same length-to-side panel-width relationship described in connection with the bottom closure 22, the ends of the fold-back panels enter into positive abutting engagement prior to completion of downfolding. The downfolding continues with crowding of paperboard stock at the abutting cut ends of the fold-back panels, until the bottom closure 22a has reached the condition illustrated in FIG. 10 at which time the ultimate seal is completed.

For the purpose of further enhancing the seal of the bottom closure 22a and eliminating incipient leakage channels which might otherwise occur, resort may be had to a plurality of concentrated pressure areas defining blocking embossments similar to those described above in connection with the bottom closure 22. Accordingly, it will be noted upon reference to FIG. 13, which is an outside view of the bottom closure 22a, that the same includes a

relatively large rectangular embossment 121 (shown in dot-dash outline) covering the overlying or outside bottom flap 112 except the area thereof overlying the tuck-in flap. By the same token, the inner major bottom panel 111 is embossed over a rectangular area 122 extending from the side seam panel to the edge of the overlying flap 116. In addition, spot embossments 124 (FIGS. 13 and 14), which in this instance happen to be of circular shape with narrow rectangular central indentations, block incipient leakage channels adjacent the free-cut edge of the tuck-in flap, and also adjacent the inside free-cut edge and the chamfered end 119 of the side seam panel extension 114. Certain of these incipient leakage channels run between the outer perimeter of the container and the central portion of the free cut edge of the bottom closure panel 115 which is exposed to the interior of the container. Another such incipient leakage channel runs from the exposed portion of the edge of the side seam panel extension 114 inside the container, along such edge and the end of the side seam panel extension, to the outer perimeter of the container (FIGS. 13 and 14). By reason of the chamfers 119, 120 and the selective distribution of sealing pressure upon the bottom closure 22a, the overlapping plies of the side seam extension 114 and the inside panel 111, as well as the overlapping plies of the tuck-in flap 115 and overlying flap 116 become substantially coplanar, eliminating objectionable bulges on the outer surface of the bottom closure.

We claim as our invention:

1. A container of paperboard or the like having an overall surface of thermoplastic material that becomes adhesive when subjected to heat, said container comprising, in combination, a tubular body, a top closure overlying said body, first and second pairs of opposed bottom closure panels connected to said body, said second pair of bottom closure panels being triangular in shape and infolded between said body and said first pair of bottom closure panels, two pairs of triangular fold-back panels each pair of which is connected to a respective one of said triangular bottom panels and to respective ones of said first pair of opposed bottom closure panels, said fold-back panels also having cut edges and being folded against the inside surface of said first pair of opposed bottom panels, the combined length of said fold-back panels along said opposed bottom panels of said first pair being greater than the length of the base of the adjoining triangular bottom panel whereby said fold-back panels are crowded together along their cut edges upon infolding and sealing of said bottom closure panels.

2. A container of paperboard or the like having a surface of thermoplastic material that becomes activated adhesively when subjected to heat, said container comprising, in combination, a tubular body, a top closure overlying said body, a first pair of opposed bottom closure panels connected to said body, a second pair of opposed bottom closure panels also connected to said body, said second pair of bottom closure panels being triangular in shape and infolded between said body and said first pair of bottom closure panels, two pairs of triangular fold-back panels each pair of which is connected to a respective one of said triangular bottom panels and to respective ones of said first pair of opposed bottom closure panels, said fold-back panels also having cut edges and being folded against the inside surface of said first pair of opposed bottom panels and with adjacent edges of each said pair of fold-back panels abutting each other, the combined length of said fold-back panels along said opposed bottom panels of said first pair being greater than the length of the base of the adjoining triangular bottom panel whereby said fold-back panels are abuttingly crowded together along their cut edges upon infolding and sealing of said bottom closure panels, and an overlying flap integral with one of said first pair of bottom closure panels and adapted to extend over the other bottom closure panel

in said first pair beyond the abutting edges of said fold-back panels.

3. A container of paperboard or the like having an overall surface of thermoplastic material that becomes activated adhesively when subjected to heat, said container comprising, in combination, a body, a top closure on said body, first and second pairs of opposed bottom closure panels connected to said body, said second pair of bottom closure panels being triangular in shape and infolded between said body and said first pair of bottom closure panels, two pairs of triangular fold-back panels each pair of which is connected to a respective one of said triangular bottom panels and to respective ones of said first pair of opposed bottom closure panels, said fold-back panels also having cut edges and being folded against the inside surface of said first pair of opposed bottom closure panels and with adjacent cut edges of each said pair of fold-back panels abutting each other, the combined length of said fold-back panels along each said opposed bottom closure panel of said first pair being greater than the length of the base of the adjoining triangular bottom panel whereby said abutting cut edges of said fold-back panels are crowded together upon infolding and sealing of said bottom panels, a tuck-in flap integral with one of said first pair of bottom closure panels and inserted between the other bottom closure panel of said first pair and the fold-back panels thereagainst, and an overlying flap integral with and extending over the other one of said first pair of bottom closure panels, said overlying flap extending over and beyond said tuck-in flap.

4. A container of paperboard or the like having an overall surface of thermoplastic material that becomes activated adhesively when subjected to heat, said container comprising the combination of a tubular body having a side seam flap, a top closure on said body, first and second pairs of opposed bottom closure panels connected to said body, a side seam panel extension secured to one of said first pair of bottom closure panels, a relieved end portion on said side seam panel extension, said second pair of bottom closure panels being triangular in shape and infolded between said body and said first pair of bottom closure panels, two pairs of triangular fold-back panels each pair of which is connected to a respective one of said triangular bottom panels and to respective ones of said first pair of opposed bottom closure panels, said fold-back panels being folded against the inside surface of said first pair of opposed bottom panels and with adjacent edges of each said pair of fold-back panels abutting each other tightly throughout their entire length, and an overlying flap integral with the other one of said first pair of bottom closure panels, said overlying flap being constructed and arranged to extend over the first one of said first pair of bottom closure panels and beyond the abutting edges of said fold-back panels to effect a thermoplastically sealed margin between said abutting edges and the exterior of said container, said overlying flap having a relieved portion substantially complementary to said relieved end portion of said side seam panel extension.

5. A blank for a container of foldable sheet material having an overall surface of thermoplastic material that becomes adhesive when subjected to heat, said blank comprising, in combination, a plurality of side panels, a plurality of top closure panels, first and second pairs of bottom closure panels alternately connected to said side panels as extensions thereof, said second pair of bottom closure panels being triangular in shape, two pairs of triangular fold-back panels each pair of which is connected to a respective one of said triangular bottom panels and to respective ones of said first pair of opposed bottom closure panels, each said pair of fold-back panels having a common free cut edge, the combined length of said fold-back panels along said bottom closure panels of said first pair being greater than the length of the base of the adjoining triangular bottom panel whereby said fold-back

panels are adapted to be crowded together along their free cut edges upon infolding and sealing of said bottom closure panels.

6. A container of paperboard or the like having an overall surface of thermoplastic material that becomes activated adhesively when subjected to heat, said container comprising the combination of a tubular body, a top closure overlying said body, first and second pairs of overlapping opposed bottom closure panels connected to said body, said second pair of bottom closure panels being triangular in shape and infolded between said body and said first pair of bottom closure panels, two pairs of triangular fold-back panels each pair of which is connected to a respective one of said triangular bottom panels, said fold-back panels being folded against the inside surface of said first pair of opposed bottom panels and with adjacent edges of each said pair of fold-back panels abutting each other, an overlap flap integral with one of said first pair of bottom closure panels, the other bottom closure panel of said first pair having an overlapped edge with its central portion exposed to the interior of the container, said overlap flap being constructed and arranged to extend over the other bottom closure panel of said first pair and beyond the abutting edges of said fold-back panels, and means defining blocking indentations in at least said one of said first pair of bottom closure panels adjacent said overlapped edge of said other bottom closure panel between the central portion of said edge and the outer perimeter of said container, whereby incipient leakage channels are blocked and the fluidtight integrity of said container is maintained.

7. A container of paperboard or the like having an overall surface of thermoplastic material adapted to become activated adhesively when subjected to heat, said container comprising, in combination, a tubular body, a top closure on said body, first and second pairs of overlapping opposed bottom closure panels connected to said body, a side seam panel extension secured to one of said first pair of bottom closure panels, said side seam panel extension having an end portion and an inner edge, said inner edge having a portion exposed to the interior of the container, said second pair of bottom closure panels being triangular in shape and infolded between said body and said first pair of bottom closure panels, two pairs of triangular fold-back panels each pair of which is connected to a respective one of said triangular bottom panels, said fold-back panels being folded against the inside surface of said first pair of opposed bottom panels and with adjacent edges of each said pair of fold-back panels abutting each other, the other bottom closure panel of said first pair having an overlapped edge with its central portion exposed to the interior of the container, indentations in at least said one of said means defining blocking first pair of overlapping opposed bottom closure

panels adjacent said overlapped edge between the central portion thereof and the outer perimeter of the container, and means defining blocking indentations in at least one of said first pair of bottom closure panels between said exposed portion of said inner edge of said side seam panel extension and the outer perimeter of said container.

8. A container of foldable sheet material having a thermoplastic surface that becomes activated adhesively when subjected to heat, said container comprising, in combination, a body, a top closure on said body, first and second pairs of opposed bottom closure panels connected to said body, a side seam panel extension secured to one of said first pair of bottom closure panels and having an inner edge and a projecting end, said second pair of bottom closure panels being triangular in shape and infolded between said body and said first pair of bottom closure panels, two pairs of triangular fold-back panels each pair of which is connected to a respective one of said triangular bottom panels, said fold-back panels being folded against the inside surface of said first pair of opposed bottom closure panels and with adjacent edges of each said pair of fold-back panels abutting each other, a tuck-in flap integral with one of said first pair of bottom closure panels and inserted between the other bottom closure panel of said first pair and the fold-back panels thereagainst, said tuck-in flap having an overlapped edge, an overlap flap integral with and extending over the other one of said first pair of bottom closure panels, said overlap flap extending over and beyond said tuck-in flap, said overlap flap having a relieved portion substantially complementary to said projecting end of said side seam panel extension, and means defining blocking indentations in said first pair of bottom closure panels at the overlapped edge of said tuck-in flap and at said inner edge and projecting end of said side seam panel extension.

9. A blank for a container as defined in claim 5, having an overlapping flap integral with one of said first pair of bottom closure panels.

10. A blank for a container as defined in claim 5, having a tuck-in flap integral with one of said first pair of bottom closure panels.

UNITED STATES PATENT OFFICE
CERTIFICATE OF CORRECTION

Patent No. 3,120,335

February 4, 1964

Harry B. Egleston et al.

It is hereby certified that error appears in the above numbered patent requiring correction and that the said Letters Patent should read as corrected below.

Column 9, line 52, after "container," insert -- means defining blocking --; line 53, strike out "means defining"; line 54, strike out "blocking".

Signed and sealed this 23rd day of June 1964.
